UNITED STATES PATENT OFFICE.

AXEL APPELBERG, OF SCHENECTADY, NEW YORK, ASSIGNOR TO GENERAL ELECTRIC COMPANY, A CORPORATION OF NEW YORK.

TUNGSTEN-FURNACE.

1,000,620.

Specification of Letters Patent. Patented Oct. 24, 1911.

Application filed October 18, 1908. Serial No. 457,982.

To all whom it may concern:

Be it known that I, AXEL APPELBERG, a subject of the King of Sweden, residing at Schenectady, county of Schenectady, State 5 of New York, have invented certain new and useful Improvements in Tungsten-Furnaces, of which the following is a specification.

This invention relates to electric furnaces 10 and embodies an apparatus in which metals and compounds can be heated and treated at temperatures approaching the vaporizing point of tungsten and without the danger of contaminating the materials under treatment with carbon, oxygen, or other foreign elements.

My improved furnace is of the resistance type and is provided with a resistance conductor consisting of substantially pure metal 20 operative at an exceedingly high temperature, and furthermore, the furnace is provided with all adjuncts necessary or convenient to ready use on an industrial scale or as a means for laboratory investigations at 25 high temperatures under conditions hitherto unattainable. I have hereinafter described a furnace as embodying a resistance conductor of tungsten, and I consider that this metal is typical of the general class of refractory metals which may be used to advantage in the furnace hereinafter described.

The details of one embodiment of my invention are illustrated in the drawings forming a part of this specification, in which—

Figure 1 is an elevation partly in section; Fig. 2 is another section taken at right angles to Fig. 1; Fig. 3 is a plan; and Fig. 4 is a detail of the insulated joint through which current is introduced to the resistance members of the furnace.

The furnace comprises an air-tight metal chamber 1 fitted with a cover 2 through which extends a metal tube 3 whereby the chamber may be connected with a vacuum pump and may be exhausted and maintained in an exhausted condition throughout the operation of the furnace; or whereby the chamber may first be exhausted and then 50 filled with hydrogen or other gas inert with respect to the tungsten of the heater but capable of effecting desired chemical changes in material under treatment. I prefer to make the metal chamber 1 of cast gun-metal

and I provide it with tubular extensions 4 and 5 having rubber closures 6 and 7 which can be removed if desired.

The metal chamber 1 is inclosed in a metal jacket 8 through which water may be circulated to cool the chamber. Within the metal chamber 1, two tubular tungsten heaters 9 and 10 are arranged with their tops inclosed respectively in tungsten bushings 11 and 12 clamped in copper terminal blocks 13 and 14 to which electrical connection is established by water cooled brass tubes 15 and 16 passing through the cover 2 of the furnace and insulated therefrom as shown in detail in Fig. 4. Each of these brass tubes is shaped like a U and each forms one terminal of the furnace. The air-tight joint between the current supply tube 15 and the cover 2, as shown in detail in Fig. 4, embodies a screw threaded sleeve 17 soldered to tube 15 and provided with a clamping nut 18 insulated from the top of the furnace by a paper washer 19. An annular ring 20, also of paper, insulates the sleeve 17 from the furnace top and rests on a mica washer 21 separating two lead collars 22 and 23. The tungsten tubes 9 and 10 are at their lower ends held respectively in the tungsten bushings 24 and 25 clamped in a copper base block consisting of a central casting 26 having semicylindrical segments 27 and 28 bolted thereto, these segments being supported by a plate 29 having openings therein in line with the cylindrical openings of the tungsten heaters and also in line with the tubular extensions 4 and 5 of the metal chamber 1.

About each tubular tungsten heater is arranged a heat reflecting screen consisting of an outer tungsten tube 30, an inner tungsten tube 31, and a packing of alumina or other inert powder between the tubes. A tungsten bushing 32 may be used to support the inner tube 31 on the lower inturned edge of the outer tube 30. The entire screen is supported on three lava buttons 33 resting on the copper base block and serving as electrical insulators. This base block maintains electrical connection between the lower ends of the tungsten heaters, so that current entering through one of the brass tubes 15 or 16 passes downward through one tungsten tube and then across through the copper block and up the other tube.

It so happens that tungsten and some of the other exceedingly refractory metals, when made up in large tubes such as are here disclosed, undergo a sort of progressive shrinkage or gradual decrease in length during normal use, particularly during the early part of their life. To avoid any inconvenience from this cause, the present furnace is provided with spring actuated means for maintaining a tight contact between the tungsten tubes and their respective terminals. To this end, a water cooled brass tube 34 of the complex yoke shape shown in Fig. 1 passes through the copper base block 26 and has both ends extending upward through the cover 2, from which they are respectively insulated by rubber sleeves 35 and 36. A spiral spring 37 is secured to the upper ends of these tubes by a clamp 38 and is so supported from an adjustable bolt 39 that a definite and predetermined pull can be exerted on the brass tube 34 and thereby made available to insure firm pressure and good contact between the tungsten tubes and their upper and lower copper blocks or terminals. I consider this feature as of very considerable importance, for it entirely eliminates arcing at the ends of the tungsten tubes. The tungsten tubes above described, may be made by carrying out the process described in the paragraph beginning with line 79, page 1 of my U. S. Patent # 953,774, issued April 5, 1910. After the tubes become seasoned by heating to a temperature higher than 1300° C. as described in the above mentioned patent, the furnace can be operated at temperatures much higher than 1300° C. and in fact, approaching the melting point of tungsten, which is something above 3000° C. I prefer to use alternating current for the furnace and for 9 inch tungsten tubes with an internal diameter of 2 inches and a thickness of one-eighth of an inch, I may use 5000 amperes or even more.

It will be readily understood that a furnace of this type can be calibrated as to temperature, and that thereafter, any particular condition of temperature and gas pressure can be duplicated with certainty merely by regulating the current supply, the degree of exhaustion, etc.

This furnace can be used for a great variety of technical and scientific work, such as for instance as the reduction of oxids by hydrogen at high temperatures, the production of alloys of the more refractory metals, such as tungsten, molybdenum, titanium, thorium, uranium, etc., the vaporization of refractory oxids, such as magnesia, and the fusion of other oxids such as alumina or calcium oxid, all in an atmosphere free from carbon. The furnace has proved very servicable for the production and treatment of tungsten and molybdenum filaments either

in a vacuum or in an atmosphere of hydrogen. The furnace may be used for the continuous heat treatment of such metals without danger of contaminating the charge by vapors or by charged particles given off by the heating elements. The entire absence of carbon anywhere within the furnace permits the attainment of the highest temperatures without danger of producing a carbid.

When the furnace is being run as a vacuum furnace for the treatment of metal filaments, I prefer to suspend those filaments from brass tubes 40 and 41 passing through cover 2 and separated therefrom by rubber sleeves 42 and 43. Each of these brass tubes is provided with a glass window 44 in line with the hot zone of the furnace, thus enabling the operator to watch the progress of the heat treatment. These brass tubes may also be provided with tubular inlets 45, which are closed when the furnace is used as a vacuum furnace but which may be used as hydrogen inlets when the furnace is used as a hydrogen furnace.

As a means for holding a bundle of filaments 46 within the tungsten tube, I may utilize a saddle comprising a tungsten bar 47 suspended by a tungsten or molybdenum wire 48. After the filaments have been given the desired heat treatment in a vacuum, air or hydrogen may be admitted to the furnace and then on removal of the tubes 40 and 41 with their inclosing rubber sleeves 42 and 43, the filaments may be lifted out through the cover 2 without detaching that cover from the furnace chamber 1. This is a great convenience when filaments are being treated on a commercial scale.

In case the furnace is being run as a hydrogen furnace, I prefer to keep it filled with hydrogen at atmospheric pressure and to introduce the filament or whatever is being treated through the tubular extensions 4 and 5 at the bottom of the furnace, the rubber blocks 6 and 7 being removed to permit this. The lightness of the hydrogen prevents it from escaping at the bottom of the furnace, and the furnace charge, carried in a suitable crucible or suspended over a framework of tungsten, can be introduced and withdrawn from the hot zone of the furnace without contaminating the inert atmosphere of that zone and without the inconvenience of cooling down the furnace after each run or of unbolting the cover or otherwise partially dismantling the furnace.

If a circulation of hydrogen through the hot zones appears desirable, it may be obtained by admitting streams of hydrogen through the tubes 40 and 41 at the top of the furnace and allowing that hydrogen to escape through the extensions 4 and 5 at the bottom of the furnace, though when these

extensions are plugged up, the hydrogen can be taken off through the exhaust pipe 3 at the top of the furnace.

What I claim as new and desire to secure 5 by Letters Patent of the United States, is,—

1. In an electric furnace, the combination of a chamber, a tungsten heater therein, means for supplying an inert gas to the chamber, and an opening in the bottom of 10 the chamber through which material to be heated can be introduced in proximity to said tungsten heater.

2. In an electric furnace, the combination of a tubular tungsten heater, and means for 15 maintaining a hydrogen atmosphere circulating in and about said heater while material to be heated is being introduced therein.

3. In an electric furnace, the combination 20 of a chamber, means for supplying an inert gas thereto, and a tubular tungsten heater within said chamber, said chamber having openings through which material to be heated can be introduced while the tungsten 25 heater is at normal running temperature.

4. In an electric furnace, the combination of a chamber, a plurality of tungsten heaters within said chamber, means connecting said heaters in series and spring-actuated 30 means holding said connecting means in close contact with said heaters.

5. In an electric furnace, a chamber having a sealed cover, heating members supported from said cover and connected in series, 35 and openings in said cover through which

material to be heated can be introduced into said chamber or can be withdrawn therefrom.

6. In an electric furnace, the combination of a chamber having a cover, a plurality 40 of resistance heaters supported from said cover, a block electrically connecting said heaters, and a liquid cooled yoke connected with said block and a spring located outside said chamber supporting said yoke. 45

7. In an electric furnace, the combination of a chamber, a tungsten heater herein, current supply terminals therefor, and means outside of said chamber for adjusting the contact pressure between terminals and 50 heater.

8. In an electric furnace, the combination of a chamber, a resistance heater therein, terminals for said heater and means actuated by a spring located outside of said 55 chamber for holding said terminals in contact with said heater irrespective of its shrinkage.

9. In an electric furnace, the combination of a chamber, a plurality of resistance heaters therein, a block electrically connecting said heaters, and a spring-supported yoke holding said block in contact with said heaters. 60

In witness whereof, I have hereunto set 65 my hand this 9th day of October, 1908.

AXEL APPELBERG.
